UNITED STATES PATENT OFFICE.

CHARLES C. TOMKINSON, OF PLAINFIELD, NEW JERSEY, ASSIGNOR TO J. EDWARD OGDEN, OF MOUNTAINVILLE, NEW YORK.

DOOR MECHANISM.

Application filed October 11, 1922. Serial No. 593,710.

To all whom it may concern:

Be it known that I, CHARLES C. TOMKINSON, a citizen of the United States, and a resident of Plainfield, county of Union, and State of New Jersey, have invented certain new and useful Improvements in Door Mechanisms, of which the following is a specification.

This invention relates to doors such as are used for closing large openings in warehouses, pier sheds and like structures and more particularly to a common type of such doors which are mounted to raise and swing inwardly to inclined or horizontal position in order to conserve head room. Counterbalancing means is provided to facilitate the operation of the doors.

One object of the invention is to provide counterbalancing means for the link type of door having a vertical component effective during the break out of the door whereby the door opening movement is facilitated.

Another object of the invention is to provide positive and effective means for guiding the door to its closed position in such a manner as to overcome any lateral pressure against the door such as wind pressure.

Another object of the invention is to secure the proper opening and closing of doors of the character described and the retention thereof in closed position.

Further objects of the invention will appear from the following description taken in connection with the drawings which form a part of this application and in which,

Fig. 1 is a diagrammatic elevational view showing in closed position a door constructed in accordance with the invention.

Fig. 2 is an elevational view similar to Fig. 1 but showing the door sections in partially open position.

Fig. 3 is an elevational view showing the door sections in full open position.

Fig. 4 is an elevational view on an enlarged scale showing the link connection to the upper door section.

Fig. 5 is an elevational view similar to Fig. 4 but showing the link latch in engagement with the latch releasing member.

Fig. 6 is an elevational view partly in section on an enlarged scale showing the means for guiding the door during its break out movement.

The invention may be briefly described as a door comprising a plurality of sections

mounted for vertical and lateral movement. Mechanism is provided for raising the lower section or sections to a position overlapping the upper section and for subsequently raising and swinging the sections as a unit laterally to inclined or horizontal position. The door is supported by link structure and this link structure is so connected to the door that the effective length of the link or links is varied during the initial movement of the sections in unison or during the break out movement. Means is provided for engaging and guiding the door during the break out movement and for counterbalancing both sections during this movement thereby facilitating the door opening movement. Further details of the invention will appear from the following description.

As shown in the drawings the door comprises an upper section 10 and a lower section 11. The lower section has secured adjacent its lower end rollers 12 disposed in suitable guideways and the upper section is provided with the usual means for guiding the lower section in its vertical movement. The lower section 11 also has secured thereto laterally projecting lugs or brackets 13 adapted to engage the lower edge 14 of the upper section when the lower section has been raised to a position overlying the upper section.

A separate counterbalancing mechanism may be provided for each door section if desired but in the form of the invention illustrated a single counterbalancing weight 15 has secured thereto a sheave 16 around which passes a cable 17. One end of this cable is connected at some suitable point preferably as shown at 18 intermediate the upper and lower edges to the upper door section 10. The other end of the cable 17 is connected to the lower door section at a suitable point preferably a point near the lower end of this section as shown at 19. The two ends of the cable 17 pass over a pair of sheaves 20 and 21 respectively to the upper and lower door sections. In the form of the invention shown these two sheaves are mounted on a single shaft 22 and the sheave 21 is secured fast to the shaft and the sheave 20 is rotatably mounted thereon.

The upper door section is supported by link mechanism including a link 23 pivoted at 24 to a fixed bracket 25 carried by the building structure in which the door is

mounted. The main supporting link 23 is connected to the upper door section through an intermediate or auxiliary link 26, the two links being pivotally connected at 27 and the 5 link 26 being pivoted to the upper door section at 28. As the upper door section is engaged and raised by the lower door section, the link 23 swings laterally and the link 26 folds on the link 23 to the position shown in 10 Fig. 2.

Means is provided for latching the link 26 in folded position and this means comprises a latch 29 pivoted at 30 to an extension 31 of the link 23, the latch being normally 15 pulled downwardly by a spring 32. The latch 29 is adapted to engage over a projection 33 formed on the end of the link 26 and the pivot pin 28 projects beyond the link 26 and is adapted to seat in a notch 34 formed adjacent the lower end of the link 23. The latch 29 is normally retained in inoperative position by a cam 35 formed on the door casing and the latch moves to operative position when the door sections move 25 away from the door casing during their break out movement. It will thus be seen that the door has a vertical component of movement during the break out and during this movement the effective length of the link supporting mechanism is varied or 30 shortened.

Also it should be noted that during this vertical component of the door movement, the counter-balancing weight 15 is effective 35 on both the lower and the upper door sections thereby materially assisting in the break out movement of the door.

Means is also provided for facilitating the movement of the door during the break out 40 by guiding the door through an arcuate path. This means comprises a hook shaped member 40 pivoted at 41 on a bracket 42 carried by the door casing. The hook shaped end 43 of this member normally engages a stud 44 carried by the upper door section and preferably positioned near the upper edge thereof. The member 40 is retained in engagement with the stud 44 by means of a spring 45 which tends to swing the member 45 40 in a clockwise direction about the pivot 41. When the door sections are swung in unison during their break out movement the member 40 will follow the sections thereby 50 guiding the door through an arcuate path.

In the embodiment of the invention shown 55 the member 40 swings through substantially 90 degrees and is limited in its swing by a stop 46 carried by the bracket 42 and disposed in the path of movement of the member 40. The guiding member is also effective during the closing movement of the door and at a predetermined point in the closing movement the stud 44 engages the hooked end 43 and the door is thereupon positively 60 guided into closed position. The guiding

member therefore facilitates both the opening and the closing door movements by guiding the door through the break out and into closed position.

Although in the diagrammatic showings in 70 the drawing single links are illustrated, it will be understood that these links are preferably provided at each of the lateral edges of the door.

In order to support the door in its wide 75 open position shelves 60 are preferably provided in a position to be engaged by the studs 44 carried by the upper door section. These shelves may be inclined if desired in order to permit the door sections to ride upwardly thereon and as shown in Figs. 1-3 80 the connection 24 between the link 23 and the fixed bracket 25 may be formed as a pin and slot connection to permit the door to raise on the shelf brackets 60.

Although certain specific embodiments of the invention have been particularly shown and described, it will be understood that the invention is capable of further modification 90 and that further changes in the construction 95 and in the arrangement of the various co-operating parts may be made without departing from the spirit or scope of the invention as expressed in the following claims.

What I claim is:—

1. A door arranged for vertical and lateral movement and link mechanism for supporting and swinging said door comprising a pair of pivotally connected links, one link being pivoted on a fixed pivot and the other 100 link being pivoted to the door, the latter link being foldable on the other link during the vertical door opening movement.

2. A door arranged for vertical and lateral movement and link mechanism for supporting and swinging said door comprising a pair of pivotally connected links, one link being pivoted on a fixed pivot and the other link being pivoted to the door, the latter link being foldable on the other link during the vertical door opening movement, and means for retaining the link in folded position during the remaining portion of the door opening movement.

3. A door arranged for vertical and lateral movement and link mechanism for supporting and swinging said door comprising a pair of pivotally connected links, one link being pivoted on a fixed pivot and the other link being pivoted to the door, the latter link being foldable on the other link during the vertical door opening movement, means for retaining the link in folded position during the remaining portion of the door opening movement, and means for releasing said folded link at a predetermined point in the door closing movement.

4. A door arranged for vertical and lateral movement and link mechanism for supporting and swinging said door comprising a 130

pair of pivotally connected links, one link being pivoted on a fixed pivot and the other link being pivoted to the door, the latter link being foldable on the other link during the vertical door opening movement, and counterbalancing means operative on said door during the vertical movement thereof.

5. A door arranged for vertical and lateral movement, counterbalancing mechanism therefor and means for furnishing an additional counterbalancing effect during the break out movement including link supporting and swinging means comprising a plurality of inter-connected links foldable one 10 on the other during the initial break out movement.

6. A door arranged for vertical and lateral movement, counterbalancing mechanism therefor, and means for furnishing an additional counterbalancing effect during the break out movement including link supporting and swinging means comprising a pair 20 of links pivoted to and foldable on each other and having their free ends pivoted respectively to the door and to a fixed support.

7. A door arranged for vertical and lateral movement and comprising an upper and a lower section, counterbalancing means connected to the lower and upper sections and means including a pair of links, foldable one on the other, for effecting through said counterbalancing means an additional counterbalancing effect during the break out 30 movement.

8. A door arranged for vertical and lateral movement and comprising an upper and a lower section, counterbalancing means connected to the upper and lower sections and means including a pair of 40 links, foldable one on the other, for effecting through said counterbalancing means an additional counterbalancing effect during the break out movement, and releasable 45 means for retaining said links in folded

position subsequent to the break out movement.

9. A door arranged for vertical and lateral movement and comprising an upper and a lower section, counterbalancing means 50 connected to the upper and lower sections, and means including a pair of pivotally connected links, foldable one on the other and pivotally connected respectively to a fixed support and to the upper door section, for 55 effecting through said counterbalancing means an additional counterbalancing effect during the break out movement.

10. A door arranged for vertical and lateral movement and link mechanism for supporting and swinging the door, said mechanism including a link pivoted to a fixed support and having a lost motion connection so constructed and arranged that the effective length of the link is shortened when 60 the door is raised and the link is swung from supporting to swinging position.

11. A door arranged for vertical and lateral movement and link mechanism for supporting and swinging the door, said mechanism including a link pivoted to a fixed support and having a lost motion connection including a latch so constructed and arranged that the effective length of the link is shortened when the door is raised and 75 the link is swung from supporting to swinging position.

12. A door arranged for vertical and lateral movement and link mechanism for supporting and swinging the door, said mechanism including a link pivoted to a fixed support and having a connection to the door so constructed and arranged that the link will be shortened upon the initial opening movement of the door.

In witness whereof, I have hereunto set my hand this 9th day of October, 1922.

CHARLES C. TOMKINSON.

Witness:

I. B. MOORE.
